OUTDOOR RECEPTACLE COVER

Frank G. Bellek, 11143 S. Peoria, Chicago, Ill.

Filed Sept. 28, 1959, Ser. No. 57,720

Term of patent 14 years

(Cl. D26—5)

Fig. 1 is a face plan view of an outdoor receptacle cover showing my new design;

Fig. 2 is a side elevational view, the opposite side being substantially a mirror image thereof;

Fig. 3 is a face plan view thereof with a portion moved to an alternate position;

Fig. 4 is a top edge view thereof; and

Fig. 5 is a bottom edge view thereof.

I claim:

The ornamental design for an outdoor receptacle cover, as shown and described.
